DESIGN FOR CARPET.

Specification forming part of Design No. 7,207, dated February 24, 1874; application filed February 18, 1874.
[Term of Patent 3½ years.]

To all whom it may concern:

Be it known that I, THOMAS J. STEARNS, of Boston, in the county of Suffolk and State of Massachusetts, have invented a certain new and original Design for Carpets, of which the following is a specification:

The nature of my design is fully represented in the accompanying photographic illustration.

What I claim as my invention is—

A design for a carpet, as represented in the accompanying photographic illustration.

In testimony whereof I have signed my name to this specification in the presence of two subscribing witnesses.

THOMAS J. STEARNS.
